UNITED STATES PATENT OFFICE.

EMMOR HAMILTON KELLEY AND GEORGE ALVA STEWART, JR., OF SOUTH BROWNSVILLE, PENNSYLVANIA.

AUTO LIFT.

Application filed March 31, 1922. Serial No. 548,459.

To all whom it may concern:

Be it known that we, EMMOR H. KELLEY and GEORGE A. STEWART, Jr., citizens of the United States, and residents of South 5 Brownsville, in the county of Fayette and State of Pennsylvania, have invented certain new and useful Improvements in Auto Lifts, of which the following is a specification.

10 Our invention is an improvement in portable automobile lifts.

An important object of our invention is to provide a device of the above named character which is extremely easy to operate owing to the lever arrangement and simplicity 15 of construction.

Another object is to provide such a lift or jack which is adapted to give quick and effective action with the application of the 20 least amount of energy.

Other objects and advantages of the invention reside in certain novel features of construction, combination and arrangement of parts which will be hereinafter more fully 25 described and claimed, reference being had to the accompanying drawings, in which—

Figure 1 is a side elevation of the device shown in its extreme operative position,

Figure 2 is a similar view showing the device in inoperative position with the lever extended upwardly to serve as a handle to push the device into and out of engagement with the work,

Figure 3 is a top plan perspective view of 35 the device,

Figure 4 is a detail view of the axle saddle or support member, and,

Figure 5 is a detail perspective view of one of the operating levers or handles.

40 As shown in the drawings, the base rails 1 are spaced apart and rigidly connected together by the front and rear cross tie bars 3 and 4 respectively, forming a base frame for the jack or lift. This base frame is preferably composed of units of angle irons as shown but it is to be understood that any suitable construction may be employed to give strength to the base frame.

50 Two similar upright supports 5 are rigidly secured at their lower ends to the front end of the base as shown and are braced by the bracing irons 7 respectively. Lifting bars 9 forming a tiltable platform are pivotally connected to the upper portions of uprights 5 by bolts 11.

Each of the supporting bars is provided with an axle saddle or supporting member as indicated by reference numeral 13. These axle saddles may be formed of sheet metal and are stepped as at 15 for adjustment purposes.

55 Toggle links 16 and 17 are pivotally connected at their overlapping ends to each other by means of the pins 18, and are in turn pivotally connected at their outer ends to the base at 19 and to the lifting bars as at 20 respectively so that the lifting bars may be swung into and out of engagement with the object to be lifted, by merely swinging the links upon the center pin 18.

70 The swing of the links is accomplished by means of handles or operating levers 21 which, as shown in Figure 5, are preferably formed of two strips of stout metal clamped together by rivets. The rear or outer ends of the levers are substantially straight forming convenient handles for moving the device about the floor, but the front or inner extremities 22 which are spaced apart, are curved to allow the handles to assume a proper operative position when the lifting bars are down. The curved extremities 22 are pivotally connected at their front ends to the lifting bars 9 by means of the bolts 20.

75 The operating levers 21 have a rigid extension 24 riveted between its sections as shown and extending forwardly in substantial alinement with the handle portion. This extension not only serves as a support 80 for the lifting bars 9, when they are tilted into operative position, but also acts as a lock in holding the pivot point 18 slightly past a dead center or an imaginary line drawn from bolts 19 to 20, thus forming an 85 effective support for the bars 9.

90 Horizontally elongated vertical openings are formed in the levers 21 as indicated at 23, Figure 5, so that the levers will fit over the corners of the vertical flange of the base irons 1 locking the lever and toggle links in 95 position and at the same time brace the levers against lateral movement.

100 In order that the device may be easily transported from place to place we provide rollers or casters 25, at the front and rear ends of the base rails 1.

105 In use, the device is moved under the work to be lifted, as, for instance, an automobile. When the levers 21 are moved downwardly 110

on their fulcrum at 20, the extensions 24 which are carried by the levers and connected to the overlapped ends of the toggle links at their point of connection by the same 5 pivot pin 18, swing with the levers and moving forwardly and upwardly engage the bars 9 and forces the pivot points 19 and 20 further apart. In this way the platform is 10 caused to engage the work in one of the steps 15 and lift it.

It should be noted that the point 18 will move slightly past a dead center on an imaginary straight line drawn from the centers of pivots 19 and 20. In this manner the 15 supporting bars are securely held or locked in place.

It is to be understood that various changes in the size, shape, and arrangement of parts 20 of our invention may be resorted to without departing from the spirit of the invention or the scope of the claims.

We claim:—

1. A lifting device comprising a supporting rail, a tiltable member carried on said 25 rail, means carried by the tiltable member for engaging an object to be lifted and means for tilting the tiltable member, said means including a swinging lever bar pivotally connected at one end to the tiltable 30 member, and provided with a forward extension, toggle links connecting the tiltable member and the supporting rail, said toggle links being connected at their junction to the said extension of the swinging lever bar.

2. A jack comprising a base, a tiltable member pivoted thereto, toggle links connected at their outer ends to the base and 35 tiltable member and having their adjacent ends pivotally connected, and a bent lever bar connected at its bent end to said tiltable member and having a forward extension

pivoted to the adjacent ends of said links at their junction.

3. A jack comprising a base rail, a rigid standard at its front end, a lifting and supporting rail pivotally connected at its front end to said standard, toggle links pivotally connected at their outer ends to said base rail and supporting rail adjacent their rear ends, said toggle links pivotally connected at their inner ends, a bent lever pivotally connected at its bent end to said supporting rail adjacent its rear end, said lever having a rigid extension projecting forwardly at the bend thereof, said extension pivotally connected to said toggle links at their junction, the forward end of said extension adapted to engage the supporting rail and hold the same in its elevated operative position.

4. A jack comprising a base rail, a rigid standard at its front end, a lifting and supporting rail pivotally connected at its front to said standard, toggle links pivotally connected at their outer ends to the base and supporting rails respectively, and pivotally connected together at their inner ends, a bent lever pivotally connected at its bent end to the lifting rail, a rigid extension projecting forwardly from said bent lever at its bend, said extension pivotally connected forwardly of the bend to the toggle links at their junction, the forward end of said extension adapted to engage the lifting rail and hold same in its elevated operative position, said lever having an opening intermediate its ends adapted to fit over the rear end of the base rail and lock the lever against longitudinal and lateral movement.

EMMOR HAMILTON KELLEY.
GEORGE ALVA STEWART, JR.
